WASHING MACHINES

Yoshikazu Yamamoto, Higashisumiyoshi-ku, Osaka, Japan, assignor to Daiwa Kikai Kabushiki Kaisha, Wakayama, Japan

Filed Sept. 4, 1962, Ser. No. 221,056
Claims priority, application Japan Sept. 5, 1961
3 Claims. (Cl. 68—184)

This invention relates to a washing machine.

Washing machines heretofore in use, although there are many kinds, have all been more or less dependent for their operation upon friction caused by relative movements of the wash and the water currents, and owing to these very movements the wash is often not only wrenched and kept from being given an even and thorough washing, but also the area of the wash in contact with the water is decreased greatly. In addition, the wash also has its texture greatly damaged.

With this object in view the present invention comprises a tank with a rotor rotatably mounted in the tank for rotation around an axis. The rotor is a solid member having a plurality of flutings on the peripheral surface thereof, each fluting having a cross sectional shape which is outwardly convex. The flutings extend from one end of the rotor to the other at an angle to the axis of rotation. A perforated cover is positioned over the rotor, the perforated cover being circular in a cross section perpendicular to the rotor axis and fitting closely to said rotor with the apexes of the flutings sweeping closely adjacent the interior surface of the cover during rotation of the rotor.

According to the present invention, in wash liquid of ordinary or chemical soap (hereafter designated simply as water) in a tank there are generated wave-motions which are high in amplitude and comparatively low in frequency, and these wave motions consist of high pressure parts for compressing the wash to accelerate the water in its pervasion of the wash, and low pressure parts for expanding the wash and pressing out the water therefrom, these parts alternately reaching the floating wash, and at the same time there is generated slow circular currents which make the washing still more even, with hardly any twisting of the wash being caused by these wave motions.

Other and the further objects of the present invention will become apparent from the following specification and claims taken together with the accompanying drawings in which is shown the preferred embodiments of the washing machine according to the present invention.

FIG. 1 is a sectional elevation view of a washing machine embodying the present invention;

FIG. 2 is a plan view of a rotor for the same;

FIG. 3 illustrates diagrammatically the movements of water around the rotor;

FIG. 4 is a sectional elevation view of another embodiment of the present invention; and

FIG. 5 is a transverse section through the rotor shown in FIG. 4.

In FIGS. 1 and 2 reference numeral 11 indicates a tank and on the bottom 12 of the machine is mounted an electric motor 13. Numeral 14 indicates a rotor rotatably mounted for rotation around a vertical axis in said tank and having frusto-conical shape, driven by the electric

2

motor 13. Numeral 15 indicates a perforated cover made of a plate having a number of holes 15, and fixed to the bottom plate 16 of the tank 11, and the rotor 14 is covered with this cover 15 so closely as to leave only a small clearance between the two. To the bottom plate 16 is attached a discharge pipe 17.

The rotor 14 is a solid member having a plurality of flutings 18 on the peripheral surface thereof, said flutings 18 extending from one end of the rotor to the other, and having a cross sectional shape which is outwardly convex. In the embodiment of FIGS. 1-3, the flutings lie along the conical surface of the rotor 14. The perforated cover 15 has cross section which is circular transverse to the axis of the rotor and it fits closely to the rotor with the apexes of the flutings 18 sweeping closely adjacent the interior surface of the cover 15 during rotation of the rotor.

When the rotor 14 rotates, the front side 18₁ of each fluting 18, that is, the side facing in the rotatory direction of the rotor 14 presses against the water in contact therewith, and this water gushes out into the tank 11 through the corresponding holes 15₁ of the cover 15, so that in this part of the water there is generated a high pressure wave-motion, and in the water on the rear side 18₂ of the fluting 18, that is, the side facing in the direction opposite to that of the rotation of the rotor 14 there is generated reduced pressure, and the water outside the corresponding holes 15₂ of the cover 15 flows in therethrough, so that in this part of the water there is generated a low pressure wave-motion traveling in the opposite direction to that of said high pressure wave-motion.

The wash floating in the water in the tank 11, therefore, is rapidly washed by cooperative workings of the high pressure wave-motion and the low pressure wave-motion which alternately reach it.

The water above the rotor 14 on the axial line thereof is only very slightly affected by the pressure waves, while pressure waves are generated on the circumference of the rotor 14, so that the water in the tank 11 slowly flows in the direction of the arrows shown in FIG. 1, and with it the wash moves, every part of it being the more evenly and effectively washed.

As seen in FIGS. 4 and 5, the rotor can be substantially cylindrical in shape. The rotor 14' is shown as being cylindrical and having the flutings 18' extending from the top to the bottom thereof and being skew to the axis of rotation of the rotor. The perforated casing 15' is cylindrical in shape and fits closely around the rotor 14' with the apexes of the flutings 18' sweeping closely adjacent the interior surface of the casing. The remainder of the structure is substantially the same as the embodiment of FIGS. 1-3.

It is thought that the invention and its advantages will be understood from the foregoing description and it is apparent that various changes may be made in the form, construction and arrangement of the parts without departing from the spirit and scope of the invention or sacrificing its material advantages, the form hereinbefore described and illustrated in the drawings being merely a preferred embodiment thereof.

Having thus described my invention, what I claim and desire to secure by Letters Patent of the United States is:

1. A washing machine, comprising a tank, a rotor rotatably mounted for rotation around an axis in said tank,

said rotor being a solid member having a plurality of flutings on the peripheral surface thereof each having a cross sectional shape which is outwardly convex and said flutings extending from one end of the rotor to the other at an angle to the axis of rotation, and a perforated cover over the rotor, said perforated cover being circular in a cross section perpendicular to the rotor axis and fitting closely to said rotor with the apexes of the flutings sweeping closely adjacent the interior surface of the cover during rotation of said rotor, whereby said rotor and cover cooperate to produce an alternate movement of washing liquid outwardly of the axis of rotation of the rotor from the side of the flutings facing the direction in which the rotor is rotating and inwardly of the axis of rotation of the rotor from the side of the flutings facing away from the direction in which the rotor is rotating.

2. A washing machine as claimed in claim 1 in which

said rotor is frusto-conical in shape and said flutings are on the conical surface thereof, and said perforated cover is close to the apexes of the flutings on the conical surface and close to the top surface of the rotor.

5 3. A washing machine as claimed in claim 1 in which said rotor is cylindrical and said flutings are on the cylindrical surface thereof and skew to the axis of rotation, and said perforated cover being close to the flutings on the cylindrical surface of said rotor.
